UNITED STATES PATENT OFFICE

HARRY LEE GIBSON, OF PORT WASHINGTON, WISCONSIN, ASSIGNOR TO ECKHART COMPANY, OF PORT WASHINGTON, WISCONSIN, A CORPORATION OF WISCONSIN

DESIGN FOR A DOLL

Application filed July 30, 1928. Serial No. 27,625. Term of patent 3½ years.

To all whom it may concern:

Be it known that I, HARRY LEE GIBSON, a citizen of the United States, residing at Port Washington, in the county of Ozaukee and State of Wisconsin, have invented a new, original, and ornamental Design for Dolls, of which the following is a specification, reference being had to the accompanying drawing, forming part thereof.

I claim:

The ornamental design for a doll as shown.

HARRY LEE GIBSON.
